CLAIM

The ornamental design for headwear, as shown and described.

DESCRIPTION

FIG. 1 is a top-left-front perspective view of headwear (e.g., augmented reality display glasses), showing our new design, in a first operating position (e.g., an expanded or open configuration).

FIG. 2 is a front view thereof, in the first operating position.

FIG. 3 is a rear side view thereof, in the first operating position.

FIG. 4 is a right side view thereof, in the first operating position.

FIG. 5 is a left side view thereof, in the first operating position.

FIG. 6 is a top view thereof, in the first operating position.

FIG. 7 is a bottom view thereof, in the first operating position.

FIG. 8 is a top-left-rear perspective view thereof, in the first operating position.

FIG. 9 is a bottom-right-rear perspective view thereof, in the first operating position.

FIG. 10 is a bottom-right-front perspective view thereof, in the first operating position.

FIG. 11 is a top-left-front perspective view thereof, in a second operating position (e.g., a contracted or closed configuration).

FIG. 12 is a front view thereof, in the second operating position.

FIG. 13 is a rear side view thereof, in the second operating position.

FIG. 14 is a right side view thereof, in the second operating position.

FIG. 15 is a left side view thereof, in the second operating position.

FIG. 16 is a top view thereof, in the second operating position.

FIG. 17 is a bottom view thereof, in the second operating position.

FIG. 18 is a top-left-rear perspective view thereof, in the second operating position.

(Continued)

FIG. 19 is a bottom-right-rear perspective view thereof, in the second operating position; and,
FIG. 20 is a bottom-right-front perspective view thereof, in the second operating position.
The shade lines show contour and not surface ornamentation.
